COMBINED BAR SUPPORT AND SPACER

Bror Hillberg, Chicago, Ill., assignor to Superior Concrete Accessories, Chicago, Ill., a partnership.

Application May 16, 1945; Serial No. 594,116

9. Claims. (Cl. 94—8)

1

The present invention relates generally to combined supports and spacers for bars. More particularly the invention relates to that type of combined bar support and spacer which is primarily adapted for use with a concrete roadway joint in the form of a horizontally elongated upstanding subgrade-supported compressible strip between adjacent concrete roadway forming slabs and a series of laterally spaced substantially horizontal dowel bars having the central portions thereof extending through the strip and their ends disposed in the slabs, serves to support the joint in connection with pouring of the concrete for the slabs and also to reenforce the slabs after hardening or setting of the concrete, and as its parts comprises a rectilinear series of laterally spaced U-shaped chairs at one side of the strip corresponding in number to, and associated respectively with, the dowel bars of the joint and having the upper ends thereof shaped to form open top pockets for the adjacent ends of the dowel bars, a corresponding rectilinear series of laterally spaced U-shaped chairs at the other side of the strip having the upper ends thereof shaped to form open top pockets for the adjacent ends of the dowel bars, and crossrods extending under the compressible strip and between the two series of chairs.

One object of the invention is to provide a combined bar support and spacer of this type which is an improvement upon, and has certain advantages over, previously designed combined bar supports and spacers and is characterized by the fact that it effectively and efficiently fulfills its intended purpose and may be installed with facility and manufactured at an extremely low cost.

Another object of the invention is to provide a combined bar support and spacer of the type under consideration in which the crossrods correspond in number to the chairs of each series, the ends of the crossrods are bent upwards and have the bottom pieces of the chairs connected thereto, and the upper extremities of the upwardly bent ends of the crossrods are located at the bottom of the open top pockets at the upper ends of the chairs and serve to support the dowel bars of the joint from below.

Another object of the invention is to provide a combined bar support and spacer of the last mentioned character which comprises in addition to the two series of chairs and the crossrods a pair of horizontal spacer rods which are associated respectively with, and extend parallel to, the two series of chairs, serve to hold the crossrods in

2

laterally spaced relation and have portions thereof arranged so that they extend across the chairs and define the bottoms of the open top pockets.

A further object of the invention is to provide a combined bar support and spacer of the type and character under consideration in which the upper extremities of the upwardly bent ends of the crossrods are L-shaped in order that they are capable of supporting in parallel relation with the spreader rods comparatively thick rods for aligning the dowel rods of the roadway joint.

A still further object of the invention is to provide a combined bar support and spacer which is generally of new and improved construction and is characterized by simplicity of design and quick mounting of the aligning bars and the dowel bars.

Other objects of the invention and the various advantages and characteristics of the present combined bar support and spacer will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a perspective view showing the combined bar support and spacer embodying the invention in operative relation with a concrete roadway joint of the compressible strip and dowel bar variety; and

Figures 2, 3 and 4 are end, side and top views, respectively, of one of the chairs of the combined bar support and spacer.

The combined bar support and spacer which is shown in the drawings constitutes the preferred form or embodiment of the invention. It is primarily designed or adapted for use in connection with a concrete roadway joint J and consists of a rectilinear series of laterally spaced crossrods 5, a pair of aligning bars 6, a plurality of chairs 7, and a pair of spacer rods 8.

The joint J is adapted for disposition between a pair of adjacent roadway forming concrete slabs S on a subgrade S' and, as well understood in the art, permits the slabs to expand and contract in response to changes or variations in temperature. As its parts the joint J embodies a compressible filler strip j and a series of parallel laterally spaced horizontally extending dowel bars, j'. The strip j is formed of composition

material and fits in an upstanding position between the two concrete slabs *S*. It extends transversely with respect to the roadway that is formed by the slabs, and has the bottom surface thereof in abutment with the subgrade *S*¹. The dowel bars *j*¹ extend through holes in the central portion of the filler strip *j* and constitute load transfer members whereby the load on one of the slabs is transferred to the other slab. They are spaced equidistantly apart and extend lengthwise of the slabs *S*. In addition they are located in the same horizontal plane and are coated with grease or graphite so that during pouring of the concrete for the slabs the concrete will not adhere to them. The joint *J* also comprises in addition to the filler strip *j* and the dowel bars *j*¹ a set of sheet metal sleeves *j*². These sleeves are slidably mounted on the ends of the dowel bars that are at one side of the strip *j* and form air pockets outwards of such ends whereby sliding movement of the dowel bars is permitted in response to expansion of the slabs. As the result of the grease or graphite which is applied to the dowel bars the bars, after setting or hardening of the slabs, are free to slide longitudinally and permit the slabs to move to and from one another as the result of expansion and contraction thereof.

The combined bar support and spacer constitutes a unit for holding the joint in place during pouring of the concrete in connection with formation of the slabs *S*. It is adapted to become permanently bonded to the concrete after hardening or setting of the concrete and serves to reinforce the two slabs.

The crossrods *5* of the combined bar support and spacer are formed of comparatively stiff heavy gauge wire and correspond in number to the dowel bars *j*¹ of the joint *J*. They extend in parallel relation with, and directly underlie, the dowel bars and rest on the subgrade *S*¹, as shown in Figure 1. The central portion of the crossrods are bent to form U-shaped stirrups *9* in which the superjacent portions of the lower margin of the compressible filler strip *j* fit snugly. Said stirrups are in alignment and hold the compressible filler strip against transverse bending or distortion in connection with pouring of the concrete for the slabs *S*. The ends of the crossrods *5* are bent upwards so that they extend vertically. They are located slightly inwards of the ends of the dowel bars *j*¹ and have L-shaped upper extremities consisting of horizontally extending lower parts *10* and vertically extending upper parts *11*. The horizontally extending lower parts *10* extend inwards in the direction of the compressible filler strip *j*; and the vertically extending upper parts *11* are connected to, and project upwards from, the inner ends of the lower parts *10*, and define with the lower parts open top seats *12* for the aligning rods *6*. The latter, as shown in Figure 1, are disposed on opposite sides of, and extend parallel to, the compressible filler strip *j* and are arranged at right angles to the dowel bars *j*¹. They are snugly seated within the seats *12* and underlie and directly support the ends of the dowel bars *j*¹ of the joint *J*. The diameter of the aligning rods *6* is materially greater than that of the crossrods *5* in order that the aligning rods are rigid. The purpose or function of the aligning rods is to maintain the dowel bars in true horizontal alignment with one another. The height of the vertically extending upper parts *11* of the L-shaped upper extremities of the upwardly bent ends of the crossrods *5* corresponds to the diameter of the aligning rods *6*

to the end that when the combined bar support and spacer is in operative relation with the joint *J* the portions of the dowel bars *j*¹ that are directly inwards of the portions that are supported by the aligning rods *6* rest on the upper ends of the vertically extending upper parts *11*.

The chairs *7* are U-shaped as best shown in Figures 1 and 3 of the drawings. They are formed of stiff wire of the same gauge as the crossrods *5* and comprise substantially straight horizontally extending intermediate bottom pieces *13* and upstanding side pieces *14* and *15*. There are two chairs for each crossrod. As shown in the drawings, the chairs are disposed or positioned directly outwards of the upwardly bent ends of the crossrods *5*. The central portions of the bottom pieces *13* of the chairs are welded to the upwardly bent ends of the crossrods at points directly beneath the horizontally extending lower parts *10*. The side pieces *14* and *15* of the chairs are formed integrally with the ends of the intermediate bottom pieces *13*. They extend upwards and inwards and define at the top portions thereof restricted entrance pockets *16* for the ends of the dowel bars *j*¹. The upper extremities of the side pieces *14* and *15* are bent outwards so as to form upwardly flared mouths leading toward the entrances of the pockets *16*. The ends of the dowel bars are adapted to be inserted into the pockets by urging or shifting them downwards between the outwardly bent upper extremities of the side pieces and thence past the bends constituting the entrances to the pockets *16*. By having the upper extremities of the side pieces bent outwards the ends of the bars may be readily inserted into the pockets. When the bars are in place in the pockets they are disposed slightly beneath the bends at the upper ends of the side pieces and are held in place by such bends. The distance between the bends at the upper ends of the side pieces of the chairs is less than the diameter of the dowel bars and hence when the dowel bars are inserted into place they flex the side pieces *14* and *15* apart as they enter the entrances of the pockets *16*. After they are shifted downwards past the bends constituting the entrances to the pockets the upper ends of the side pieces *14* and *15* spring inwards and thus secure the ends of the dowel rods in place in the pockets. Because of the spacing of the bends at the upper ends of the side pieces of the chairs the bends serve when the ends of the dowel bars are shifted into the pockets to urge the dowel bars downwards into firm engagement with the upper ends of the vertically extending upper parts *11* and the subjacent portions of the aligning rods *6*. As shown in Figure 3, the bends at the upper ends of the side pieces of the chairs are disposed above the upper ends of the vertically extending upper parts *11*. The central portions of the side pieces *14* and *15* of the chairs define the outer sides of the seats *12* for the aligning rods *6*.

The spacer rods *8* are disposed on opposite sides of, and are positioned in parallel relation with, the compressible filler strip *j* of the joint *J* and serve to hold or maintain the crossrods *5* in connected and laterally spaced relation. They are formed of stiff wire of the same gauge as the crossrods *5* and the chairs *7* and are located directly outwards of the chairs. As shown in the drawings the spacer rods *8* are positioned above the bottom pieces *13* of the chairs and

70

are arranged so that the top parts thereof are in the same plane as the upper ends of the upwardly extending upper parts 11 of the L-shaped upper extremities of the upwardly bent ends of the crossrods. The portions of the spacer rods that cross or lap the lower central portions of the side pieces 14 of the chairs are welded to the latter portions. There are no welds, however, between the spacer rods 8 and the side pieces 15 of the chairs in order that such side pieces are permitted to flex freely to and from the side pieces 14. The portions of the spacer rods that extend between the side pieces 14 and 15 of the chairs form the bottoms of the restricted entrance pockets 16 for the ends of the dowel bars 11 of the joint J. When the dowel bars are in place the ends thereof rest on the portions of the spacer rods 8 that are between the side pieces 14 and 15 of the chairs as well as on the subjacent portions of the aligning rods 6 and the upper ends of the vertically extending upper parts 11 of the L-shaped upper extremities of the upwardly bent ends of the crossrods 5. The spacer rods 8 serve not only to maintain the crossrods 5 in connected and laterally spaced relation but also to maintain the crossrods so that they extend at true right angles to the aligning rods 6.

When it is desired to use the combined bar support and spacer in connection with the roadway joint J it is placed on the subgrade S, as shown in Figure 1, and arranged so that it extends transversely of the roadway. After proper positioning or arranging of the combined bar support and spacer the joint J is assembled by inserting the dowel bars 11 through the holes in the central portion of the compressible filler strip j. After insertion of the dowel bars through the filler strip the joint J is positioned over the combined bar support and spacer and manipulated so as to cause the filler strip j to extend parallel to the aligning rods 6 and the spacer rods 8 and the dowel bars 11 to extend at right angles to said rods. Thereafter the joint is shifted downwards so as to bring the lower margin of the strip j into seated relation with the stirrups 9 on the central portions of the crossrods 5 and the ends of the dowel bars into seated relation with the restricted entrance pockets 16. The ends of the dowel bars are brought into seated relation with the pockets by forcing them past the bends at the upper portions of the side pieces 14 and 15 of the chairs 7, as hereinbefore described. When the ends of the dowel bars are in seated relation with the pockets the dowel bars are maintained by the combined bar support and spacer in a truly horizontal position and also at true right angles to the compressible filler strip j. After assembly of the joint with respect to the combined bar support and spacer concrete is poured at the sides of the strip j to form the roadway slabs S. Upon setting or hardening of the concrete the dowel bars form load transfer members as hereinbefore pointed out, and the combined bar support and spacer serves as a reinforcing medium for the slabs.

The herein described combined bar support and spacer is essentially simple in design and hence may be manufactured at a low and reasonable cost. It effectively and efficiently fulfills its intended purpose and is characterized by the fact that it is in the form of a rigid unit.

Whereas the combined bar support and spacer

has been described and illustrated in connection with a roadway joint J, it is to be understood that it has other capabilities of use. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. In combination with parallel substantially horizontal bars, a combined bar support and spacer comprising a plurality of parallel substantially horizontal wire formed crossrods corresponding in number to, positioned respectively beneath, and disposed in parallel relation with, said bars and having the ends thereof bent upwards and arranged so that their upper extremities underlie and support the ends of the bars, separately formed U-shaped, small sized, wire formed chairs having the central portions of their cross pieces welded to certain side portions of the upwardly extending ends of the crossrods and the upper ends of the side pieces thereof shaped to form the sides of open top restricted entrance variety pockets for the ends of the bars, and a spacer rod extending at right angles to the crossrods and serving to hold the latter against relative lateral displacement.
2. In combination with parallel substantially horizontal bars, a combined bar support and spacer comprising a plurality of parallel substantially horizontal crossrods corresponding in number to, positioned respectively beneath, and disposed in parallel relation with, said bars and having the ends thereof extending upwards, U-shaped chairs extending at right angles to the crossrods and having the central portions of their cross pieces connected to the upwardly extending ends of said crossrods and the upper ends of the side pieces thereof shaped to form the sides of open top pockets for the ends of the bars, and a pair of spacer rods positioned at right angles to the crossrods, extending across the side pieces of the chairs, connected to certain of said side pieces of the chairs, and having the portions thereof that extend between the chair side pieces forming bottoms for the pockets.
3. In combination with parallel substantially horizontal bars, a combined bar support and spacer comprising a plurality of parallel substantially horizontal crossrods corresponding in number to, and positioned respectively beneath, and disposed in parallel relation with, said bars and having the ends thereof extending upwards and arranged so that their upper extremities underlie and support the ends of the bars, U-shaped chairs extending at right angles to the crossrods and having the central portions of their crosspieces connected to the upwardly extending ends of said crossrods and the upper ends of the side pieces thereof shaped to form the sides of open top pockets for the ends of the bars, and a pair of spacer rods positioned at right angles to the crossrods, extending across the side pieces of the chairs, connected to certain of said side pieces of the chairs, and having the portions thereof that extend between the chair side pieces positioned to form bottoms for the pockets.
4. In combination with parallel substantially

horizontal bars, a combined bar support and spacer comprising a plurality of parallel substantially horizontal crossrods corresponding in number to, positioned respectively beneath, and disposed in parallel relation with, said bars and having the ends thereof extending upwards and provided with inwardly extending L-shaped upper extremities forming open top seats, a pair of parallel laterally spaced bar aligning rods extending at right angles to the crossrods, disposed in the said seats and arranged so that they underlie and support the ends of the bars, and chairs connected to the upwardly extending ends of the crossrods and having the upper ends thereof shaped to form the sides of open top pockets for the ends of the bars.

5. In combination with parallel substantially horizontal bars, a combined bar support and spacer comprising a plurality of parallel substantially horizontal crossrods corresponding in number to, positioned respectively beneath, and disposed in parallel relation with, said bars and having the ends thereof extending upwards and provided with inwardly extending L-shaped upper extremities forming open top seats, a pair of parallel laterally spaced bar aligning rods extending at right angles to the crossrods, disposed in said seats and arranged so that they underlie and support the ends of the bars, chairs connected to the upwardly extending ends of the crossrods and having the upper ends thereof shaped to form the sides of open top pockets for the ends of the bars, and a spacer rod extending at right angles and fixedly connected to the crossrods.

6. In combination with parallel substantially horizontal bars, a combined bar support and spacer comprising a plurality of parallel substantially horizontal crossrods corresponding in number to, positioned respectively beneath, and disposed in parallel relation with, said bars and having the ends thereof extending upwards and provided with inwardly extending L-shaped upper extremities forming open top seats, a pair of parallel laterally spaced bar aligning rods extending at right angles to the crossrods, disposed in said seats and arranged so that they underlie and support the ends of the bars, U-shaped chairs extending at right angles to the crossrods and having the central portions of their cross pieces connected to the upwardly extending ends of said crossrods and the upper ends of the side pieces thereof shaped to form the sides of open top pockets for said ends of the bars, and a pair of spacer rods positioned at right angles to the crossrods and connected fixedly to the chairs.

7. In combination with parallel substantially horizontal bars, a combined bar support and spacer comprising a plurality of parallel substantially horizontal crossrods corresponding in number to, positioned respectively beneath, and disposed in parallel relation with, said bars and having the ends thereof extending upwards and provided with inwardly extending L-shaped upper extremities forming open top seats, a pair of parallel laterally spaced bar aligning rods extending at right angles to the crossrods, disposed in said seats and arranged so that they underlie and support the ends of the bars, U-shaped chairs extending at right angles to the crossrods and having the central portions of their cross pieces connected to the upwardly extending ends of said crossrods and the upper ends of the side pieces thereof shaped to form the sides of open top restricted entrance pockets for said ends of the bars, and a pair of spacer rods positioned at right

angles to the crossrods, extending across the side pieces of the chairs, connected to certain of said side pieces of the chairs, and having the portions thereof extending between the chair side pieces forming bottoms for the pockets and arranged so that the top parts thereof are in the same plane as the top parts of the aligning rods.

8. In combination with parallel substantially horizontal bars, a combined bar support and spacer comprising a plurality of parallel substantially horizontal crossrods corresponding in number to, positioned respectively beneath, and disposed in parallel relation with, said bars, and having the upper ends thereof extending upwards and provided at their upper extremities with inwardly extending horizontal lower parts and vertically extending upper parts forming with the lower parts open top sides and arranged so that the upper ends thereof underlie and support the ends of the bars, a pair of parallel laterally spaced bar aligning rods extending at right angles to the crossrods, seated in said seats and having the top parts thereof in the same plane as the upper ends of said upwardly extending upper parts and arranged to underlie and support said ends of the bars, chairs connected to the upwardly extending ends of the crossrods and having the upper ends thereof shaped to form the sides of open top pockets for the ends of the bars, and a spacer rod extending at right angles and connected to the crossrods.

9. In combination with parallel substantially horizontal bars, a combined bar support and spacer comprising a plurality of parallel substantially horizontal crossrods corresponding in number to, positioned respectively beneath, and disposed in parallel relation with, said bars, and having the upper ends thereof extending upwards and provided at their upper extremities with inwardly extending horizontal lower parts and vertically extending upper parts forming with the lower parts open top sides and arranged so that the upper ends thereof underlie and support the ends of the bars, a pair of parallel laterally spaced bar aligning rods extending at right angles to the crossrods, seated in said seats and having the top parts thereof in the same plane as the upper ends of said upwardly extending upper parts and arranged to underlie and support said ends of the bars, U-shaped chairs extending at right angles to the crossrods and having the central portions of their cross pieces connected to the upwardly extending ends of said crossrods and the upper ends of the side pieces thereof shaped to form the sides of open top restricted entrance pockets for said ends of the bars, and a pair of spacer rods positioned at right angles to the crossrods, extending across the side pieces of the chairs, connected to certain of said side pieces of the chairs, and having the portions thereof extending between the chair side pieces forming bottoms for the pockets and arranged so that the top parts thereof are in the same plane as the top parts of the aligning rods.
